H. A. KERSLAKE.
VAPOR BURNER OR PLUMBER'S TORCH.

No. 473,159.

Patented Apr. 19, 1892.

UNITED STATES PATENT OFFICE.

HARRY ANDREW KERSLAKE, OF AUBURN, ASSIGNOR TO H. P. CLARK, OF NEW YORK, N. Y.

VAPOR-BURNER OR PLUMBER'S TORCH.

SPECIFICATION forming part of Letters Patent No. 473,159, dated April 19, 1892.

Application filed December 9, 1891. Serial No. 414,485. (No model.)

To all whom it may concern:

Be it known that I, HARRY ANDREW KERSLAKE a, citizen of the United States, residing at Auburn, in the county of Cayuga and State 5 of New York, have invented certain new and useful Improvements in Vapor-Burners or Plumbers' Torches; and I do hereby declare the following to be a full, clear, and exact description of the invention, such as will enable 10 others skilled in the art to which it appertains to make and use the same.

This invention relates to certain new and useful improvements in vapor-burners or plumbers' torches adapted for use in connection with hydrocarbon fuel, preferably naphtha or gasoline, and particularly designed for use in various arts requiring the application of intense heat to a relatively small surface, as for the burning of paint, heating and fusing 15 small objects, and for soldering and various other purposes to which the blow-pipe is commonly applied.

The object of my invention is to provide a burner which requires no mechanical forced 25 draft, which shall give out a steady and constant flame of high temperature, and which is simple in construction and operation, durable, and comparatively inexpensive; and it consists of the construction and combination 30 of parts disclosed and claimed in the following specification, of which the accompanying drawings form a part, wherein similar numerals of reference designate like or equivalent parts wherever found throughout the 35 several views, and in which—

Figure 1 is a side elevation; Fig. 2, a central section; Fig. 3, a detail showing the wick; Fig. 4, a plan view with chimney and hood removed.

Referring to the drawings, reference-number 1 designates the reservoir or oil-pot, of any desired material, which should be capable of resisting considerable internal pressure, say fifty pounds to the square inch. The 40 top of the reservoir is provided with an annular depression or cavity 2, and from the center of this concavity rises a nozzle or extension 3, either formed integrally with or secured to the reservoir and forming a wick-holding socket, the top or cover of which is 45 provided with a nipple or gas-jet discharge 4,

having an aperture of exceedingly small caliber, which communicates directly with the interior of the reservoir.

Within the reservoir is the wick 5, preferably round in cross-section, and the upper end thereof is preferably inclosed in a cap 6, of wire gauze or cloth, firmly secured thereto, the spaces between the wires forming passages for oil or vapor, and the body of the 60 wick is preferably wound with wire 7 to keep the wick in shape and to control to an extent the capillary action thereof, and thus limit the amount of oil or other substance which will pass through the wick to the point of 65 vaporization, as hereinafter described. It will be seen that this wire wrapping serves simply as a compress or stricture upon the wick by which its capillary action is retarded or regulated, and it is evident that devices 70 other than a wire wrapping might be employed with similar results, and it will also be seen that the wire cap 6 aids in producing the result specified. By this construction the 75 too free supply of naphtha or other substance at the point of vaporization is prevented, as is also to a great extent the overflow thereof when the device is not in use, so common in this class of burners. The upper end of the wick, with its wire cap 6, is adapted to fit 80 tightly into the extension 3, so as to fill the latter in such manner that the fuel can reach the opening in the nipple only by means of capillary action through the wick.

Fitting tightly over the extension 3 is the 85 tube 8, within which is what is known as the "mixing-chamber" of an ordinary Bunsen burner. The tube 8 is provided with air-ingress openings 9, and the air as it enters through these openings 9 mingles with the 90 vapor as it escapes from the nozzle 4, and the product is burned as it escapes from the outer end of the tube 8. The tube 8 is formed of any desired material capable of resisting high degrees of heat and is preferably curved, as 95 shown.

The reservoir is provided with a screw-capped filling-orifice 10, and preferably with a pair of handles 11, and a hood or cover 12, attached to the reservoir by means of a bayonet-joint consisting of locking-studs 14 and angular slots 15 and provided with air-open-

ings 13, incloses the tube 8 and serves as a shield and draft-guard in windy weather.

The operation of my invention is as follows: The reservoir is first wholly or partially filled with naphtha and the filling-aperture closed. The annular cavity 2 is then filled with naphtha and ignited and the hood or cover 12 placed in position. The heat generated by the combustion of this free naphtha or other fuel heats the nozzle and upper part of the reservoir and volatilizes the naphtha within that is nearest the nipple, through which the hydrocarbon gas so generated gradually escapes to the mixing-chamber. This gas ultimately ignites through the openings 9 from the flame outside the tube 8, and, combining with the indraft of air from without, issues from the end of the tube as a blue and intensely hot flame. The naphtha originally placed in the cavity 2 and ignited is intended only to produce heat for the initial volatilization of the naphtha in the reservoir, the parts being all formed of heat-conducting material, and when burned out need not be renewed, since the heat evolved by the burning jet is ample to generate gas for said jet and for the internal pressure required to force the gas through the nipple.

The depressed top of the reservoir itself furnishes the simplest and best means for holding the naphtha or other material to be first burned for the generation of vapor; but it will of course be understood that a vessel might be employed for this purpose either secured to the tube 8 or entirely detachable, and many other changes in the construction and combination of parts may be made without departing from the scope of my invention, and I do not limit myself to the exact construction and arrangement of parts shown; but,

Having fully described said invention, its construction and operation, I claim and desire to secure by Letters Patent the following:

1. The combination, with a reservoir provided with a cover having an upward extension adapted to hold a wick and provided with a vapor-discharge opening, of a wick provided with a compress and held in said extension, substantially as shown and described.

2. The combination, with a reservoir provided with a cover having an upward extension adapted to hold a wick and provided with a vapor-discharge opening, of a wick provided with a compress and held in said extension and means for heating the extension and gen-

erating vapor, substantially as shown and described.

3. The combination, with a reservoir the top of which is provided with a wick-holding socket having a vapor-discharge opening 60 in its top, of a wick held and secured in said socket and means for heating the said socket and generating vapor, substantially as shown and described.

4. The combination, with a reservoir the 65 top of which is provided with a wick-holding socket having a vapor-discharge opening and an oil or naphtha holder adjacent thereto, of a wick held in and suspended from said socket, substantially as shown and described. 70

5. The combination, with a reservoir the top of which is provided with a wick-holding socket having a vapor-discharge opening, of a wick held and secured in said socket and a tube surrounding the same and connected therewith, provided with air-ingress openings, and means for heating the parts and generating vapor, substantially as shown and described. 75

6. The combination, with a reservoir the top of which is provided with a wick-holding 80 socket having a vapor-discharge opening and a cavity adjacent to said socket, of a wick provided with a compress and held in said socket and a tube provided with air-ingress openings surrounding the vapor-discharge opening, 85 substantially as shown and described.

7. The combination, with a reservoir the top of which is provided with a wick-holding socket having a vapor-discharge opening, of a wick provided with a compress held in said 90 socket, that end of the wick within the socket being inclosed within a cap having passages for oil or vapor, substantially as shown and described.

8. The combination, with a reservoir the 95 top of which is provided with a wick-holding socket having a vapor-discharge opening, of a wick provided with a compress and held in said socket, substantially as shown and described. 100

9. The combination, with the reservoir of a vapor-burner or plumber's torch, of a wick provided with a compress, whereby the capillary action of the wick is limited.

In testimony whereof I affix my signature in 105 presence of two witnesses.

HARRY ANDREW KERSLAKE.
